WALKING HEEL

Joe J. Ettinger, Warsaw, Ind., assignor to Zimmer Manufacturing Company, Warsaw, Ind.

Application September 4, 1946, Serial No. 694,801

5 Claims. (Cl. 128—87)

1

This invention relates to surgical appliances and especially to ambulatory splints for use after the occurrence of fractures of the lower legs.

More particularly the invention relates to the type of ambulatory splint termed a walking heel.

Such splints of this character as have heretofore been used have been commonly provided with a metallic heel plate and a rubber tread. To enable the rubber tread to have proper wearing quality it cannot be much softer and yielding under pressure than the ordinary rubber heel of commerce. While rubber of this characteristic is sufficient to absorb some of the shock of a well person's walking it does not yield enough to properly absorb the shocks given a broken leg while healing when the patient walks thereon. Attempts have been made to overcome this deficiency by the use of metallic springs such as coiled springs, between the heel plate and the tread. However, the use of coiled or other springs requires the provision of spring seats or guides and complicates the apparatus.

One important object of the present invention is to provide an improved walking heel wherein provision of simple character is made to give the user relief from all shock.

A second important object of this invention is to provide an improved walking heel wherein the shock due to walking will be absorbed by softly yielding and highly resilient rubber.

A third important object of the invention is to so distribute the shock absorbing rubber as to permit the patient's foot to rock on the floor while walking in the same manner as usually occurs with a person having full use of his legs.

A fourth important object of the invention is to so construct this invention that the use of metallic fastenings for holding the heel plate, the sole and the shock absorbing rubber in their proper relations will be eliminated.

With the above and other objects in view, as will be presently apparent, the invention consists in general of certain novel details of construction and combinations of parts hereinafter fully described, illustrated in the accompanying drawings and particularly claimed.

In the accompanying drawings, like characters of reference indicate like parts in the several views, and—

Figure 1 is a side elevation of one form of the invention.

Figure 2 is an end view of this form.

Figure 3 is a plan view of this form.

Figure 4 is a section on the line 4—4 of Figure 1.

2

Figure 5 is a side elevation of a second form of the invention.

Figure 6 is a plan view of the second form.

Figure 7 is an end view of the second form.

Figure 8 is a section on the line 8—8 of Figure 5.

In each form of the invention, as here shown, there is provided a foot plate 10, preferably of rectangular shape and having rounded corners. Each form also has a tread which is preferably of the same shape and size as the foot plate. The tread consists of an upper metallic plate and a lower rubber layer, the metallic plate being shown at 10a and the rubber layer at 11. The layer 11 is made of comparatively hard rubber such as is commonly used for the heels and soles of ordinary shoes in which these parts are made of rubber. Between each end of the plate 10a and the foot plate 10 there is interposed a block of highly resilient and softly yielding rubber as at 12. These blocks 12 may, if desired, be made of sponge rubber or other equivalent form of rubber. These blocks 12 are preferably secured to the metal plates 10 and 10a by the usual vulcanizing process of uniting metal and rubber. With the parts thus connected there is formed a unitary structure without the use of any metal except that in the plates 10 and 10a.

In the form of the invention shown in Figures 1 to 4 a U-shaped stirrup having a flat bottom 13 and a pair of legs 14 upstanding from the ends of the bottom 13 is provided. The bottom 13 is secured to the foot plate 10 by rivets 15 and extends transversely of the foot plate at its midlength. To the top of each leg 14 there is riveted an arcuate member 16 curved to generally conform to the shape of the leg, the members 16 confronting each other. This stirrup is to be embedded in the plaster cast when the latter is applied to the leg of the patient.

It will be seen that the heel plate extends longitudinally in opposite directions from the stirrup so that one end of the heel plate lies, in use, under the heel of the patient while the other end lies beneath the ball of his foot since the stirrup must lie beneath the arch of the foot.

In the form of the invention shown in Figures 5 to 8 an extension plate 17 the ends of which are rounded and project beyond the ends of the foot plate 10. This extension plate is made of metal and is secured to the plate 10 by screws 18. The extension plate, like the stirrup, is intended for embedment in the cast worn by the patient.

When this device is in use the yielding of the blocks 12 will so absorb the shocks due to walking that the patient will be practically freed from all

pain due to such shocks. Moreover, the blocks 12, being disposed between the end portions of the foot plate 10 and tread 11, permit the foot plate to have a natural rocking movement while the patient is walking.

What is claimed is:

1. In a walking heel, a metallic foot plate adapted to extend longitudinally of a wearer's foot, said heel plate being longitudinally extended to lie when worn both forwardly and rearwardly of the arch of the wearer's foot whereby one end of the plate lies beneath the wearer's heel and the other end beneath the ball of the wearer's foot, a rubber tread, and highly elastic rubber blocks interposed between said plate and tread at the ends thereof, said tread rubber being sufficiently hard to resist usage wear and said blocks being softly yieldable.

2. In a walking heel, a metallic foot plate adapted to extend longitudinally of a wearer's foot, said heel plate being longitudinally extended to lie when worn both forwardly and rearwardly of the arch of the wearer's foot whereby one end of the plate lies beneath the wearer's heel and the other end beneath the ball of the wearer's foot, a rubber tread, and highly elastic rubber blocks interposed between and coherently attached to said plate and tread at the ends thereof, said tread rubber being sufficiently hard to resist usage wear and said blocks being softly yieldable.

3. In a walking heel, a metallic foot plate adapted to extend longitudinally of a wearer's foot, a tread having an upper metallic layer and said heel plate being longitudinally extended to lie when worn both forwardly and rearwardly of the arch of the wearer's foot whereby one end of the plate lies beneath the wearer's heel and the other end beneath the ball of the wearer's foot, a lower rubber layer vulcanized to the upper layer, and highly elastic rubber blocks interposed between and vulcanized to the foot plate and the metallic tread layer at the ends of said foot plate, said rubber tread layer being sufficiently hard to resist usage wear and said blocks being softly yieldable.

4. In a walking heel, a metallic foot plate adapted to extend longitudinally of a wearer's foot, a tread having an upper metallic layer and said heel plate being longitudinally extended to lie when worn both forwardly and rearwardly of the arch of the wearer's foot whereby one end of the plate lies beneath the wearer's heel and the other end beneath the ball of the wearer's foot, a lower rubber layer vulcanized to the upper layer, highly elastic rubber blocks interposed between and vulcanized to the foot plate and the metallic tread layer at the ends of said foot plate, said rubber tread layer being sufficiently hard to resist usage wear and said blocks being softly yieldable, and a stirrup riveted to said heel plate centrally between the locations of said blocks.

5. In a walking heel, a metallic foot plate adapted to extend longitudinally of a wearer's foot, a tread having an upper metallic layer and said heel plate being longitudinally extended to lie when worn both forwardly and rearwardly of the arch of the wearer's foot whereby one end of the plate lies beneath the wearer's heel and the other end beneath the ball of the wearer's foot, a lower rubber layer vulcanized to the upper layer, highly elastic rubber blocks interposed between and vulcanized to the foot plate and the metallic tread layer at the ends of said foot plate, said rubber tread layer being sufficiently hard to resist usage wear and said blocks being softly yieldable, and an extension plate secured to the top of the heel plate.

JOE J. ETTINGER.
